CLAIM

The ornamental design for a baby bottle holder, as shown and described.

DESCRIPTION

FIG. 1 is a perspective view of a baby bottle holder showing my new design;

FIG. 2 is a reduced front elevational view thereof, the rear being identical;

FIG. 3 is a side elevational view of FIG. 2, both sides being identical;

FIG. 4 is a top plan view of FIG. 2; and,

FIG. 5 is a bottom plan view of FIG. 2.
